UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,255,733.

Specification of Letters Patent.

Patented Feb. 5, 1918.

Application filed November 21, 1914. Serial No. 873,258.

To all whom it may concern:

Be it known that I, FRANZ A. FULLER, a citizen of the United States, residing at Newark, in the county of Essex and State of New Jersey, have invented certain new and useful Improvements in Bag-Fasteners, of which the following is a specification, reference being had therein to the accompanying drawings, which form a part thereof.

10 My invention relates to bag fasteners and more particularly to a type thereof applicable to bag frames having pivotally connected frame members and embodying therein a lift latch adapted to lock said frame members when closed.

15 In bag frames of the character above referred to, two hinged frame members formed of channeled metal stock are used, and the bag body is secured to the frame by having the edges thereof inserted in the channel of said members. These edges may be held in the frame members in any desired manner or by any desired or well known means.

20 The channel of the frame members being ordinarily narrow and relatively deep, great difficulty has been heretofore encountered in mounting the lift latch and its controlling spring in relation to the frame member carrying the same. Furthermore, the ordinary construction of this lift latch mechanism has been such as to interfere with the connection of the bag body to the frame members.

25 A bag fastener made in accordance with my invention is so constructed that its attachment to the frame members may be accomplished without obstructing the channel in either of the body members. By thus keeping these channels free of obstruction, the frame members may be more readily covered, and a proper, substantially uniform clearance for the insertion of the edges of the bag body at all points of the frame members, is secured.

30 The controlling spring for the lift latch member is located exteriorly of the frame member, being situated within and concealed by, a box-like support mounted upon the frame member; and said spring is so constructed that the assembling of the support in relation to the frame member will develop the requisite tension in the spring. This spring when in tension will be subjected to a torsional stress having a normal tendency

35 to tilt the lift member or knob toward the keeper or catch carried by the other frame member, and also to a direct tension, away from the other members, having the same operative tendency, while permitting that slight side sway of the lug upon said lift member or knob incidental to the actuation thereof.

40 The construction of the bag fastener is such as to permit the convenient assembling of the various parts entering therewith with a minimum of operations, and this mechanism may be assembled in the frame in a manner to preserve the artistic lines of the frame.

45 The invention consists primarily in a bag fastener embodying therein a frame consisting of hinged frame members, a box-like support having an opening in the top thereof, a lift member or knob provided with a lug adapted to project through said opening and within said support, a spring, one portion of which is adapted to be operatively connected with said lug and another portion of which is projected downwardly and across 50 said support whereby it is adapted, when the support is mounted upon said frame member, to engage the top of said frame member and subject said spring to a torsional and a lateral stress adapted to normally seat said 55 lift member or knob, and a nose or catch carried by the other frame member adapted to be operatively engaged by said lift member; and in such other novel features of construction and combination of parts as are 60 hereinafter set forth and described and more particularly pointed out in the claim hereto appended.

55 Referring to the drawings:

Figure 1 is a perspective view of a bag 65 frame embodying therein my improved bag fastener;

Fig. 2 is a section upon a larger scale on the line 2-2 of Fig. 1;

Fig. 3 is a bottom view of the box-like 70 member with the lift member or knob and spring in position therein;

Fig. 4 is a detailed view of the spring;

Fig. 5 is a detailed view of the box-like 75 member; and

Fig. 6 is a detailed view of a similar box-like member carrying the nose or catch.

Like letters refer to like parts throughout the several views.

80 In the embodiment of my invention shown 110

in the drawings, the frame members are shown at $a-b$, the main body of said members being provided with hinge members $a'-a^2$; $b'-b^2$ respectively. Said hinge members are pivotally connected at $c-c'$. In the form of the invention shown the frame members $a-b$ are composed of channeled metal stock. The faces of said members presented toward each other when the bag is closed are substantially parallel so that these members may be brought close together. In the drawings, the members $a-b$ are shown as being substantially rectangular in cross-section, thus presenting a flat top. The bag fastener shown in the drawings is especially adapted for frame members of this configuration, although as it will hereinafter appear, the configuration of the frames is immaterial so long as a suitable bearing surface is afforded adjacent the lift member or knob for the purpose of engaging and tensioning the spring.

In conjunction with the frame member a , I provide a box-like support d having a substantially flat top, and pendant sides $d'-d^2$ adapted to have a sliding fit over the said frame member. The top of said support is provided with lugs e adapted to pass through openings in the frame member a and be upset within said frame. The sides $d'-d^2$ are provided respectively with lugs $f-f'$ adapted to fold over and be clenched upon the lower edges of the said frame member. The top of the support d is pierced at g to provide an opening through which the lug of the lift member or knob is adapted to pass so as to be presented within said support. The opposite ends of the top of the support d are drawn downwardly slightly to act as stops for the purpose of providing clearance between the top of said support and the top of the frame member a for the free movement of the lug of the lift member or knob.

The lift member or knob h is of the usual construction and is provided with the usual pendant rim h' adapted to coöperate with a nose or catch upon the other frame member b . Pendant from the member or knob h is a lug i adapted to have operatively connected therewith the controlling spring for said member or knob. This lug ordinarily is provided with a spring socket extending longitudinally therethrough which socket is angular so as to afford a proper seat for an angular portion of a spring.

Carried within, and concealed by, the support d is the lift member or knob controlling spring consisting of a looped spring one arm j of which is angularly formed, as at j' , to have a sliding fit with the socket in the lug i , and the other arm k of which extends parallel therewith and has its end k' turned at an angle thereto so as to be projected downwardly and inwardly of said support to a

point below the lug i . The end k' projects beyond the end j' so that when said spring is assembled in relation to the lift member or knob, it will be at one side of the lug i . The length of the turned end k' is preferably such as not to exceed the width of the top of the support d .

I provide the frame member b with a similarly constructed, box-like member l having riveted thereto a nose or catch member m and provided with a loop n carrying the pull o . The support l is attached to the frame member b by means of lugs in the same manner as the support d .

When the lift member or knob h has been assembled in the box-like support d by the insertion of the lug i thereof through the opening in the said support, the angular end j' of the spring $j-k$ is slipped into the socket in said lug; thus bringing the turned end k' beyond said lug so positioning it that it is presented downwardly and inwardly of the said support. The sides $d'-d^2$ of the support are then slipped over the frame a and the lugs e inserted through the openings in the top of the frame a . As the support d is forced to place, the spring end k' engages the top of the frame. The subsequent movement of the support imparts such movement to said end k' as to develop torsional stresses upon the entire arm k with a resultant torsional and direct stress upon the arm j . These stresses will have the effect of normally holding the member or knob h downwardly.

By using a looped spring having parallel arms, the free end of one arm being adapted to be operatively connected with the lift latch lug i and the end of the other arm being turned at an angle so as to engage a suitable bearing surface on the top of the frame member, the mounting of the support for the lift knob upon the frame member will impart a rotative movement to the spring arm having its end so turned with a resultant slight torsional and direct tension of the other arm.

When it is desired to release the latch, side pressure upon said member or knob will raise it sufficiently against the tension of the spring $j-k$, the length of the spring arm j being sufficiently great to compensate for the side sway by reason of the eccentricity of the lug i .

It will be observed that all of the operative parts of the latch mechanism are supported within box-like members, the supports d and l , including the pull. In the assembling of the device, the only obstructions within the frame members will be the various lugs used for attaching these supports which will be so clenched as to be substantially flush with the walls of the frame members. It will also be observed that it is merely necessary to slide the end

of the spring in the spring socket, which operation is much simplified by the fact that the spring is not in tension when it is connected to the lift member or knob.

The tensioning of the spring results solely from the assembling of the box-like support with the frame member. When the spring has once been tensioned the relation of parts is such that under the ordinary conditions of use, the spring cannot be disconnected from its support or so disarranged as to prevent its acting upon the lift member or knob to normally close same.

It is not my intention to limit the invention to the precise details of construction shown in the drawings, it being apparent that such may be varied without departing from the spirit and scope of the invention.

Having described the invention what I

claim as new and desire to have protected by Letters Patent is:—

A bag fastener embodying therein a frame consisting of hinged frame members, a box-like support embracing one of said members, a lift member or knob mounted on said support, and a controlling spring for said lift member or knob mounted within said support, and provided with means whereby the positioning of said support upon its frame member will tension said spring. 25

In witness whereof I hereunto affix my signature in the presence of two subscribing witnesses, this 14th day of November, 1914.

FRANZ A. FULLER.
